CARL E. WEBBER, OF SACO, MAINE, ASSIGNOR TO SACO-LOWELL SHOPS, OF BOSTON,
MASSACHUSETTS, A CORPORATION OF MASSACHUSETTS.

UNWINDING DEVICE.

1,332,654.

Specification of Letters Patent.

Patented Mar. 2, 1920.

Application filed June 4, 1917. Serial No. 172,601.

To all whom it may concern:

Be it known that I, CARL E. WEBBER, of Saco, in the county of York and State of Maine, a citizen of the United States, have 5 invented a new and useful Improvement in Unwinding Devices, of which the following is a full, clear, and exact description, reference being had to the accompanying drawings, forming a part of this specification, in 10 explaining its nature.

The present invention relates to a device or arrangement whereby thread or yarn may be withdrawn or unwound from a package with a substantially constant tension, and 15 is especially designed in accordance with the essential object of my invention, to make possible a proper tensional control of yarn unwound from a freely rotatable package by means of a lateral or side draw and this, 20 moreover, irrespective of the form of such package or manner of "wind" thereon.

It is my further object by my invention to improve the "spooler", so called, where 25 yarn is drawn laterally from a cop or bobbin and wound onto a spool, by eliminating the usual type of holder for the cop or bobbin, which has many disadvantages, and in place employing an ordinary type of rotary spindle which may be used under all circumstances.

My invention can best be seen and understood by reference to the drawings, in which—

Figure 1 is a side elevation of a spindle 35 and cop or package thereon together with the attachment comprising my invention.

Fig. 2 is a longitudinal vertical section of certain of the structural parts of which reference will hereinafter be made.

Fig. 3 is an end elevation of the structure 40 shown in Fig. 1, but with the bobbin removed.

Fig. 4 is a section on the line 4—4 of Fig. 1 with the bobbin removed.

Referring to the drawings:—

1 represents the base of a spindle having a flange-forming end portion or head 2. 3 is the spindle blade which turns within the base 1 in the usual manner. 4 is the whirl 45 fixed to the blade. 5 is a yarn package, cop or bobbin carried by the spindle. The spindle including the base is supported as follows:—

6 is a plate or casting forming both a sup-

port for parts presently to be referred to 55 and also a clamp member. 7 is the other clamp member. The base 1 of the spindle passes through both of these clamp members with the head 2 thereof bearing against the clamp member or plate 6. Arranged upon 60 the body of the spindle is a nut 8 which bears against the clamp member 7 and is retained by a keeper 9. The clamp members 6 and 7 are preformed to clamp onto a stud or post 10 which forms a part of the machine 65 (not shown) in connection with which the spindle is used. When the nut 8 is tightened its bearing against the clamp member 7 will draw the head 2 against the clamp member 6 thereby securing the base portion 70 of the spindle to the plate 6, and by the drawing together of the clamp members, fixing both this plate and also the base of the spindle to the post 10.

Fixed to the plate or casting 6 below the 75 spindle is a rod 11. This rod extends forward from the plate 6 in substantial parallel alignment with the blade and beyond the end of the yarn package thereon. At its outer end the rod is turned upwardly and 80 laterally by a bend 12 and thence projects inwardly by an extension 13 which is parallel with the initial extension 11 of the rod and accordingly with the blade of the spindle. The extension of the part 13 of 85 the rod is to a point beyond the inner end of the yarn package.

The rod 11 is mounted to be adjustable 90 extensibly, rotatably and laterally. For this purpose the inner end of the rod extends through a slot 14 cut in the plate or casting 6. The end of the rod so extending is threaded, and arranged thereon on opposite sides of the plate 6 are nuts 15 and suitably interposed washers 16. The rod is 95 fixed to the plate in any adjusted position simply by the successive operation of loosening and tightening the nuts 15.

Mounted to turn upon the rod 11 acting as a support is a swivel member 18. This is 100 held from endwise displacement by cross-pins 19. Fastening into the head of this swivel member is a drop wire 20. This wire extends through an opening tapped within the swivel head and is secured to it by means 105 of binding screws 21. The swivel is arranged about the center of the rod 11 and from the swivel the wire extends by a por-

tion 22 having an upward and backward inclination to a point beyond the inner end of the yarn package. There the wire is provided with a bend 23 from which it projects 5 with a forward extension 24 in parallel alinement with the rod 11 and spindle blade. The portion 24 of the wire projects forward beyond the end of the yarn package from 10 which point the wire is again bent to form 10 a turned end or hook 25.

Arranged to bear against the whirl is a 15 brake 26. This brake is borne by a hub 27 arranged to turn upon a post or stud 28 fixed to the plate or casting 6. The brake 20 is controlled by an arm 29 secured to the hub 27, and in which connection it will be observed by reference to Figs. 3 and 4 that the brake and its controlling arm, both 25 borne by the connecting hub 27, have the general form of a bell crank lever. That portion of the brake which bears against the 30 whirl is lined with raw-hide 30 or other friction-producing material.

The further relative arrangement, adaptation 25 and operation of the parts is as follows:—

The form, disposition and pivotal support 30 of the drop wire is such that the portion 24 of the wire will turn upon an arc toward 35 and away from the package or cop. Its normal tendency will be to gravitate and fall away from the yarn package or cop owing to the fact that the wire together with the 40 head of the swivel to which it is secured will overbalance the opposing portion of the 45 swivel. Such opposing portion of the swivel is, however, so weighted that the overbalance of the drop wire is relatively slight. The form and arrangement of the drop wire 50 is, also, such that the end portion 23 of the wire will be brought to bear against the arm 29 of the brake for lifting the brake into an inoperative position when the drop wire is elevated by movement in the general direction 55 of the cop, the movement being stopped by the engagement of the wire with the hub 27 after the arm has been turned slightly. Proper positioning of the drop wire is obtained by the adjustable positioning of the 60 rod 11 upon which it is mounted, this being obtained as before explained.

In the operation of the device the thread *a* 65 will draw from the package over the extension 13 of the rod 11, thence will pass upwardly beneath the portion 24 of the drop wire. During the unwinding of the yarn the spindle and package borne by it will be 70 rotated and the frictional resistance of the spindle to such unwinding will exert tension upon the yarn, assuming that the unwinding does not unduly accelerate the 75 speed of rotation of the spindle and assuming, also, that the draw upon the yarn is substantially constant. The draw of the 80 60 yarn being thus resisted, the resultant ten-

sional effect thereon will overcome the tendency of the drop wire to gravitate away from the bobbin, and consequently the wire will be raised and drawn toward the package until the end 23 thereof engages the arm 70 75 29 of the brake and thereupon by such engagement the brake will be lifted to an inoperative position in relation to the whirl and so maintained as long as the engagement continues. Accordingly the spindle 75 will be permitted to freely rotate though tending to exert tension upon the yarn by reason of its frictional resistance, that is, as long as no undue acceleration of the spindle is obtained and it continues to rotate at a 80 normal speed. When, however, the motion of the spindle is accelerated, as it is accelerated when the yarn is pulling off those 85 portions of the package of lesser diameter than other portions thereby causing the spindle to "race" at times, then the ensuing slack upon the yarn, assuming the draw upon the yarn to continue constant, will permit the drop wire to gravitate away from the arm 24 which allows the brake to resume its normal position and engage the 90 whirl, thereby offering added resistance to prevent undue acceleration of the spindle and restoring it to its normal speed of rotation, when the action will again elevate the 95 drop wire and move the brake into its inactive or passive position.

The action of the brake is obviously intermittent, the brake acting only when occasion requires. Moreover, the action is a 100 quick action, there being very little perceptible movement in the brake and drop wire, their entire operation being attended simply by a slight flutter or vibration of these 105 parts, evidencing the sensitiveness of the device. The resulting effect is that the spindle will be controlled to operate at a substantially constant or normal rate of speed consistent with the draw upon the yarn, and accordingly the yarn will be withdrawn with 110 a substantially constant tension, and no slack will ensue, all slack being instantly taken up.

During the unwinding of the yarn it will 115 vibrate backward and forward beneath the wire 24 depending as it draws from different portions of the cop or package, and the yarn is kept from running off the end of the wire 24 at any time by means of the hook 25 on the end of this wire. The rod 120 extension 13 is also useful during the operation of the parts in providing a support and guide for the yarn in its passage to the drop wire especially when slack occurs in the yarn owing to acceleration in the rotary speed of 125 the spindle.

Having thus fully described my invention, I claim and desire to secure by Letters Patent of the United States:—

1. In a device of the character specified, 130

- the combination comprising a spindle mounted whereby it may be rotated by the pull of yarn drawn laterally from a package carried by the spindle, a releasable normally active brake for controlling the rotary speed of the spindle, a drop wire normally maintained to exert no operative influence upon said brake, and means for mounting said drop wire whereby the yarn drawn from the package will elevate said wire to engage said brake and thereby render the same inactive, and whereby also, the dropping of the wire released by the yarn will release said brake to become active.
2. In a device of the character specified, the combination comprising a spindle mounted whereby it may be rotated by the pull of yarn drawn laterally from a package carried by the spindle, a releasable normally active gravity actuated brake for controlling the rotary speed of the spindle, said brake having an arm by which it may be moved into a position where the brake is inactive, means for pivotally mounting said brake, a drop wire normally maintained to exert no operative influence upon said brake, and means for mounting said drop wire whereby the yarn drawn from the package will elevate said wire to engage said arm and thereby render the brake inactive, and whereby, also, the dropping of the wire released by the yarn will release the brake to become active.
3. In a device of the character specified, the combination comprising a spindle having a whirl and which spindle is mounted whereby it may be rotated by the pull of yarn laterally wound from a package carried by the spindle, a releasable normally active friction brake, means for pivotally mounting said brake whereby it may engage said whirl, said brake having an arm by which it may be moved to a position out of engagement with said whirl, a drop wire normally maintained to exert no operative influence upon said brake, and means for mounting said drop wire whereby the yarn drawn from the package will elevate said wire to engage said arm and thereby render the brake inactive, and whereby, also, the dropping of the wire released by the yarn will release the brake to become active.
4. In a device of the character specified, the combination comprising a spindle mounted whereby it may be rotated by the pull of yarn drawn laterally from a package carried by the spindle, a releasable normally active brake for controlling the speed of the spindle, said brake having an arm extending from it by which it may be turned to and maintained in a disengaging position, a drop wire extending by said arm whereby it may have direct engagement therewith, said wire extending also by said spindle and package thereon whereby the yarn unwinding from
- the spindle may pass beneath said wire, means for mounting said drop wire whereby it may be elevated by the draw of the yarn against it to engage said arm and thereby elevate and maintain said brake in a disengaging position, and whereby also said drop wire will be permitted to drop by gravity releasing said brake to become active when the tension upon the yarn is lessened by undue acceleration of the rotary speed of the spindle.
5. In a device of the character specified, the combination comprising a rotary spindle arranged whereby it may be rotated by the pull of yarn drawn laterally from a package carried by the spindle, said spindle having a blade, a whirl carried by the blade and a base in which the blade is mounted to rotate, a fixture for supporting said spindle by connection with the base thereof, a normally active friction brake pivotally arranged to occupy an engaging or disengaging position with relation to said whirl, said brake having an arm by which it may be turned, means for pivotally supporting said brake, a drop wire beneath which the yarn passes as it is unwound from the package and which wire is normally maintained to exert no operative influence upon said brake, a support for said drop wire, means for fixing said support, and means for pivotally mounting said drop wire on said support whereby the wire may be elevated by the draw of the yarn against it to engage said arm and thereby move said brake into a disengaging position, and whereby, also, the drop wire will be permitted to drop, releasing said brake to become active when the tension upon the yarn is lessened by undue acceleration of the rotary speed of the spindle.
6. In a device of the character specified, a spindle arranged whereby it may be rotated by the pull of yarn drawn laterally from a package carried by the spindle, a normally active brake for controlling the speed of the spindle, said brake having an arm by which it may be turned to and maintained in a disengaging position, means for mounting said brake to occupy an engaging or disengaging position with relation to said spindle, a drop wire extending in part by said arm whereby it may have direct engagement with it, said wire extending also by said spindle and package thereon substantially parallel therewith whereby the yarn unwinding from the spindle may pass beneath said wire, a fixed supporting rod for said drop wire, said fixed rod having a turned end extending by said spindle and package thereon substantially parallel therewith and over which turned end of the fixed rod the yarn passes before passing beneath said drop wire, and means for pivotally securing said drop wire to its supporting rod where-

by it may be turned thereon and control said brake, depending upon the tension upon the arm.

7. In a device of the character specified, a
6 spindle arranged whereby it may be rotated
by the pull of yarn drawn laterally from
a package carried by the spindle, a normally
active gravity actuated brake for controlling
the rotary speed of the spindle, means for
10 mounting said brake to occupy an engaging
or disengaging position in relation to said
spindle, a drop wire beneath which the yarn
passes as it is unwound from the package

and which wire is normally maintained to
exert no operative influence upon said brake, 15
said wire being arranged also whereby it
may be lifted by the pull of the yarn and
engage said brake and move it into a disen-
gaging position, and maintain it in such
position during the ordinary and normal 20
running of the spindle, a fixed support for
said drop wire, and a weighted swivel form-
ing member pivotally mounted upon said
support and to which the drop wire is se-
cured.

CARL E. WEBBER.
